PARTITIONED CARTON

Walter J. Tyrseck, Montville, Conn., assignor to
 Robertson Paper Box Company Incorporated,
 Montville, Conn., a corporation of Connecticut

Application August 8, 1950, Serial No. 178,187

3 Claims. (Cl. 229—28)

1

This invention relates to cartons.

It is an object of the invention to provide an improved compartmented carton.

A further object of the invention is to provide a folding carton in which a single blank may be used to form an outer box, center partition and cross partitions, the collapsed box being capable of setting up by merely applying pressure to its edges.

With these objects, as well as others which will appear, in mind, a carton embodying the invention in a preferred form will now be fully described with reference to the accompanying drawing and then be more particularly pointed out in the appended claims.

In the drawing:

Figure 1 is a flat view of a blank used for making the carton;

Figures 2, 3 and 4 show the progressive foldings and gluings involved in producing the collapsed carton;

Figure 5 is a back view of the collapsed carton of Figure 4;

Figure 6 is a plan view showing the carton expanded or opened up and with the bottom flaps closed in readiness for insertion of the contents;

Figure 7 is a section on the line 7—7 of Figure 6; and

Figure 8 is a section on the line 8—8 of Figure 6.

The box selected for illustration has twelve compartments, formed by a longitudinal partition and five cross partitions to either side thereof.

The box walls are formed from an aligned series of panels 1, 3, 5, 7 and 9 arranged for folding on the score lines 2, 4, 6 and 8.

Bottom panels or flaps 11, 13, 15 and 17 are provided to form a bottom closure and are hingedly connected to the wall panels along score lines 12, 14, 16 and 18. Bottom panel 11 is formed with cut outs 19 and 20, as shown, and panel 15 carries a locking element 21, hinged to it on score lines 22 and having projections 23 and 24 for cooperating with the cuts 19 and 20 in the known manner.

Top panels or flaps 25, 27 and 29 are hinged to the wall panels on score lines 26, 28 and 30, and panel 29 has a tuck-in extension or flap 31 hingedly connected to it on score line 32.

Panels 33 and 35, hingedly connected to panels 1 and 5 along score lines 34 and 36, are the elements forming the partitions. In the carton shown, the compartments are to be of equal size, and the outer edge 38 of the panel 35 terminates short of fold line 2 at one end of wall panel 1 by a distance equaling half the width of adjacent

2

panel 3. The other end of edge 38 extends beyond the corresponding other end of wall panel 1, by a like distance. The panel 33 has thus the general outline of a slant parallelogram rather than the usual rectangle.

Similarly, outer edge 40 of panel 35 extends beyond fold line 4 by half the width of panel 3 and falls short of fold line 6 by a like amount. Panels 1 and 5 are shown as longer than panels 3 and 7, in the ratio of about two-to-one. Rectangular boxes of other shapes may be formed by changing this ratio, but in any event, panels 1 and 5 will be of equal width, and panels 3 and 7 will be of equal width, where a rectangular box is desired.

Panels 33 and 35 are shaped and cut out as shown, having a series of diagonal cuts 42, transverse cuts 44 and longitudinal cuts 46. The ends of transverse cuts 44 are connected to the diagonal cuts 42 by longitudinal score lines 48 and the longitudinal cuts 46 are continued by longitudinal score lines 50 which also meet the diagonal cuts 42. These various cuts and fold lines divide each of the panels 33 and 35 into the following elements: an inner marginal portion (43 in Figure 8) running along fold line 34 or 36, as the case may be, and which will lie flat against the corresponding wall 1 or 5 in the completed box; an outer marginal portion (45 in Figure 8) which is to form the longitudinal partition; and a number of diagonal strips (47 in Figure 8) which form the cross partitions.

In forming the carton from the blank of Figure 1, the areas *a* and *b* are first spot glued and panels 33 and 35 are folded over onto panels 1 and 5 and joined thereto, as shown in Figure 2.

Next, one or both of the panels 33 and 35 is spot glued over an area *c* and the blank is folded over on line 2, adhesively joining the marginal elements of panels 33 and 35 together, and producing the structure of Figure 3.

Finally, area *d* of panel 1 is spot glued and the blank is folded over on line 6, adhesively joining panels 1 and 9 and producing the collapsed carton of Figure 4.

The collapsed carton of Figure 4 is opened up by pressing its ends toward each other and the bottom flaps are folded to close the bottom putting the carton in the condition of Figure 6, ready for loading.

The completed box thus comprises a number of panels forming the walls and a central partition formed of the outer edge strips 38 and 40 and partition forming panels together with the diagonally extending strips 47 connecting the cen-

ter partition to the opposite side walls to form cross partitions. In Figure 1 the angle of the cuts 42 to the hinge line 34 (which angle is the same in the other partition forming panel 35) is indicated at A, and the length of the diagonal strip from vertical fold line 48 to vertical fold line 50 is indicated at D. By reason of the fact that the partition forming panels are first folded over on the wall panels to which they are attached, and that they swing in an arc in opening out from collapsed condition to the condition of Figure 6, the angle of slant of strips 47 as shown in Figure 8 will be the same angle A as indicated in Figure 1. Thus (apart from the usual allowance for thickness of materials and folds) it will be seen that the length of the strip 47 (D) multiplied by the cosine of the angle A will be equal to one half the width of panel 3 or panel 7. It will secondly be observed that the movement of the center partition in opening out the carton from collapsed condition does not move the center partition vertically so that this partition may be located at proper depth in the box by suitably selecting the width of the partition forming panels 33 and 35 as measured at right angle to hinge lines 34 and 36. While a carton of twelve compartments is shown, it will be apparent that the same principles of construction may be applied to form cartons having various numbers of compartments. For example, cutting out part of the alternate strips 47 will permit the production of a carton having six compartments, and so on.

What is claimed is:

1. A blank for forming a partitioned folding carton, comprising an aligned series of panels foldable to form a rectangular box structure, and

5
10
15
20
25

a pair of partition forming panels hinged to the edges of two alternate wall panels, each such partition forming panel being generally of the form of a slant parallelogram, having a strip adjacent its hinge edge foldable flat against the wall panel to which it is attached, a strip adjacent its opposite edge positioned for attachment to the corresponding strip of the other partition forming panel when the partition panels are folded over on the wall panels and the wall panels are folded over on their score lines, and a plurality of diagonal slits forming diagonally extending strips connecting said edge strips.

2. A blank according to claim 1, in which each partition forming panel also has score lines hinging the ends of the said diagonally extending strips to the said strips adjacent the said panel hinge line and opposite edge and extending substantially parallel to the score lines between the wall panels.

3. A blank according to claim 2, in which the angle of the slits to the partition forming panel hinge lines is such that its cosine multiplied by the length of a strip substantially equals half the width of the wall panel separating the two said opposite wall panels.

WALTER J. TYRSECK.
